(57) **ABSTRACT**

There is provided a constant current circuit having a current characteristic satisfactory in a high voltage circuit while being low in manufacturing cost. The constant current circuit includes a high breakdown-voltage depletion type NMOS transistor and a low breakdown-voltage depletion type NMOS transistor connected in series between a first terminal and a second terminal. The low breakdown-voltage depletion type NMOS transistor includes a first depletion type NMOS transistor and a second depletion type NMOS transistor connected in series. The high breakdown-voltage depletion type NMOS transistor has a gate connected to a connecting point of the first depletion type NMOS transistor and the second depletion type NMOS transistor.

CONSTANT CURRENT CIRCUIT

RELATED APPLICATIONS

Priority is claimed on Japanese Patent Application No. 2018-162908, filed on Aug. 31, 2018, the content of which is incorporated herein by reference.

BACKGROUND OF THE INVENTION

1. Field of the Invention

The present invention relates to a constant current circuit.

2. Description of the Related Art

There is a constant current circuit having a current characteristic satisfactory even in a high voltage circuit. A constant current circuit **300** as a related art is illustrated in FIG. 3. The constant current circuit **300** consists of a low breakdown-voltage depletion type NMOS transistor **30** and a high breakdown-voltage depletion type NMOS transistor **31**.

The NMOS transistor **30** has a source and a gate which are respectively connected to a terminal N2 and a drain connected to a source of the NMOS transistor **31**. The NMOS transistor **31** has the source, a drain connected to a terminal N1 and a gate connected to the terminal N2 and the gate of the NMOS transistor **30**.

Since a drain-source voltage of the NMOS transistor **30** is limited to an absolute value or less of a threshold voltage of the NMOS transistor **31**, the constant current circuit **300** is capable of reducing a variation in current due to a channel-length modulation effect of the NMOS transistor **30** and obtaining a stable constant current (refer to, e.g., Japanese Patent Application Laid-Open No. 2005-222301).

SUMMARY OF THE INVENTION

In the constant current circuit **300**, however, the low breakdown-voltage NMOS transistor **30** and the high breakdown-voltage NMOS transistor **31** are configured that the absolute value of the threshold voltage of the high breakdown-voltage NMOS transistor **31** is larger than an absolute value of a threshold voltage of the low breakdown-voltage NMOS transistor **30** for the purpose of operating as a constant current circuit. That is, in the case where since there is a restriction on the threshold voltage of the high breakdown-voltage NMOS transistor **31**, it is different in threshold voltage from a similar high breakdown-voltage NMOS transistor, a process of providing high breakdown-voltage NMOS transistors different in threshold voltage is required. Thus, the constant current circuit **300** takes high manufacturing cost.

An object of the present invention is to provide a constant current circuit having a current characteristic satisfactory in a high voltage circuit while being low in manufacturing cost.

According to one aspect of the present invention, there is provided a constant current circuit which includes a high breakdown-voltage depletion type NMOS transistor having a drain connected to a first terminal and a source, and a low breakdown-voltage depletion type NMOS transistor having a drain connected to the source of the high breakdown-voltage depletion type NMOS transistor and a source connected to a second terminal, the low breakdown-voltage depletion type NMOS transistor including a first depletion type NMOS transistor and a second depletion type NMOS

transistor connected in series, the high breakdown-voltage depletion type NMOS transistor further having a gate connected to a connecting point of the first depletion type NMOS transistor and the second depletion type NMOS transistor.

In a constant current circuit of the present invention, a gate voltage of a high breakdown-voltage depletion type NMOS transistor can be made high by connecting a gate of the high breakdown-voltage depletion type NMOS transistor to a connecting point of a low breakdown-voltage first depletion type NMOS transistor and a low breakdown-voltage second depletion type NMOS transistor. The constant current circuit is therefore capable of greatly decreasing restrictive conditions related to a threshold voltage of the high breakdown-voltage depletion type NMOS transistor for allowing the low breakdown-voltage depletion type NMOS transistor to operate in saturation and reducing its manufacturing cost.

BRIEF DESCRIPTION OF THE DRAWINGS

FIG. 1 is a circuit diagram illustrating an example of a constant current circuit according to an embodiment of the present invention;

FIG. 2 is a circuit diagram illustrating another example of the constant current circuit according to the embodiment; and

FIG. 3 is a circuit diagram illustrating a constant current circuit as a related art.

DETAILED DESCRIPTION OF THE PREFERRED EMBODIMENTS

Preferred embodiments of the present invention will hereinafter be described with reference to the accompanying drawings.

FIG. 1 is a circuit diagram illustrating a constant current circuit **100**, wherein the constant current circuit **100** is an example of a constant current circuit according to an embodiment of the present invention. The constant current circuit **100** includes depletion type NMOS transistors **10** and **11** serving as a low breakdown-voltage depletion type NMOS transistor, and a high breakdown-voltage depletion type NMOS transistor **12**.

The NMOS transistor **10** has a source and a gate which are respectively connected to a terminal N2 and a drain connected to a source of the NMOS transistor **11**. The NMOS transistor **11** has a gate connected to the terminal N2 and a drain connected to a source of the NMOS transistor **12**. Each of the NMOS transistors **10** and **11** is low breakdown-voltage depletion type NMOS transistor and has a lower breakdown-voltage than a breakdown-voltage of the NMOS transistor **12**. The NMOS transistor **12** has a drain connected to a terminal N1 and a gate connected to the drain of the NMOS transistor **10** and the source of the NMOS transistor **11**. That is, the gate of the NMOS transistor **12** is connected to a connecting point of the NMOS transistors **10** and **11**. As described above, in the constant current circuit **100**, the low breakdown-voltage depletion type NMOS transistor contains the NMOS transistors **10** and **11**, and is configured by the NMOS transistors **10** and **11** which are connected in series.

The constant current circuit **100** is configured to satisfy an equation (1) in order to allow the NMOS transistor **11** to operate in saturation. The equation (1) is expressed by

wherein VD_{11} is a drain voltage of the NMOS transistor **11**, VN_2 is a voltage of the terminal **N2**, VG_{11} is a gate voltage of the NMOS transistor **11**, and VTH_{10_11} is a threshold voltage in a case where the NMOS transistor **10** and the NMOS transistor **11** are considered to be one NMOS transistor.

Further, the drain voltage VD_{11} of the NMOS transistor **11** can be represented by a following equation

$$VD_{11}-VN_2=VG_{12}-VN_2-VTH_{12} \quad (2),$$

wherein VG_{12} is a gate voltage of the NMOS transistor **12** and VTH_{12} is a threshold voltage of the NMOS transistor **12**.

Since the gate of the NMOS transistor **11** is connected to the terminal **N2**, an equation (3) is obtained from the equation (1) and the equation (2), and expressed by

$$VG_{12}-VN_2>VTH_{12}-VTH_{10\_11} \quad (3).$$

The constant current circuit **100** is configured to take the gate voltage VG_{12} of the NMOS transistor **12** from the drain of the NMOS transistor **10** and is therefore capable of satisfying the equation (3) even if, for example, the threshold voltage VTH_{12} is higher than the threshold voltage VTH_{10_11} . As a result of satisfying the equation (3), the constant current circuit **100** enables the NMOS transistor **11** to operate in saturation because the equation (1) is satisfied.

As described above, the low breakdown-voltage depletion type NMOS transistor in the constant current circuit **100** is divided into the NMOS transistors **10** and **11**. Further, the constant current circuit **100** is configured to take the gate voltage of the high breakdown-voltage NMOS transistor **12** from a connecting point of the two NMOS transistors **10** and **11**. The constant current circuit **100** including the above-mentioned configuration is capable of adjusting the gate voltage of the high breakdown-voltage NMOS transistor **12** by adjusting the voltage of the drain of the NMOS transistor **10**, and is thereby capable of satisfying the restrictive conditions related to the threshold voltage of the NMOS transistor **12** for allowing the NMOS transistor **11** to operate in saturation without the process of providing high breakdown-voltage NMOS transistors different in threshold voltage. The constant current circuit **100** needs greatly less restrictive conditions related to the threshold voltage of the NMOS transistor **12** for allowing the NMOS transistor **11** to operate in saturation than the constant current circuit configured by a single depletion type NMOS transistor, such as the conventional current circuit **300**. Further, the constant current circuit **100** does not need the process of providing high breakdown-voltage NMOS transistors different in threshold voltage, and therefore manufacturing cost of the constant current circuit **100** can be reduced.

Incidentally, there may be a case where the saturation operation of the NMOS transistor **11** is severe from the relation between the threshold voltage VTH_{12} and the threshold voltage VTH_{10_11} . In this case, the number of divisions of the low breakdown-voltage NMOS transistor may be increased to take the gate voltage of the NMOS transistor **12** from a higher voltage. Further, in terms of an L length of the low breakdown-voltage NMOS transistor, the

length ratio of the NMOS transistor **10** to the NMOS transistor **11** may be increased.

FIG. 2 is a circuit diagram illustrating the constant current circuit **200**. The constant current circuit **200** is another example of the constant current circuit according to the present embodiment. The constant current circuit **200** is different from the constant current circuit **100** in that a gate of a low breakdown-voltage NMOS transistor is connected to a terminal **N3** instead of the terminal **N2**. That is, in the constant current circuit **200**, a voltage applied to the gate of the low breakdown-voltage NMOS transistor is different from that of a source of the low breakdown-voltage NMOS transistor.

In the constant current circuit **200**, an equation (4) is yielded from the equation (1) and the equation (2), and expressed by

$$VG_{12}>VG_{11}+VTH_{12}-VTH_{10\_11} \quad (4).$$

In this case, although the constant current circuit **200** becomes severe in condition in terms of only the voltage VG_{11} as compared with the constant current circuit **100**, the constant current circuit **200** can cope with such a severe condition by taking the gate voltage of the NMOS transistor **12** from a higher voltage. That is, it is possible to cause the low breakdown-voltage NMOS transistor to operate in saturation without changing the threshold voltage of the high breakdown-voltage NMOS transistor.

Although the embodiments of the present invention have been described above, the present invention is not limited to the above embodiments. Various changes can be made thereto within the scope not departing from the gist of the present invention.

What is claimed is:

1. A constant current circuit comprising:

a high breakdown-voltage depletion type NMOS transistor having a drain connected to a first terminal and a source; and
a low breakdown-voltage depletion type NMOS transistor having a drain connected to the source of the high breakdown-voltage depletion type NMOS transistor and a source connected to a second terminal, the low breakdown-voltage depletion type NMOS transistor including a first depletion type NMOS transistor and a second depletion type NMOS transistor connected in series,

the high breakdown-voltage depletion type NMOS transistor further having a gate connected to a connecting point of the first depletion type NMOS transistor and the second depletion type NMOS transistor.

2. The constant current circuit according to claim 1, wherein the first depletion type NMOS transistor and the second depletion type NMOS transistor respectively have gates connected to the second terminal.

3. The constant current circuit according to claim 1, wherein the first depletion type NMOS transistor and the second depletion type NMOS transistor respectively have gates connected to a third terminal.
